(57) **CLAIM**

The ornamental design for a shoelace attachment for holding a visibly distinctive panel, as shown and described.

DESCRIPTION

FIG. 1 is a front and side perspective view of a shoelace attachment for holding a visibly distinctive panel, showing my new design in use attached to shoelaces;

FIG. 2 is a front perspective view thereof;

FIG. 3 is a side view thereof, the unshown opposite side being of identical appearance;

FIG. 4 is a front view thereof;

FIG. 5 is a top view thereof, the unshown bottom view being of identical appearance; and,

FIG. 6 is an exploded front perspective view thereof showing the interaction between the shoelace attachment and visibly distinctive panel.

The broken line showing of the panel is included for the purpose of illustrating environmental structure and forms no part of the claimed design.
